ADOLPH OTT, OF NEW YORK, N. Y., ASSIGNOR TO ANTONIO PELLETIER, OF WASHINGTON, DISTRICT OF COLUMBIA.

Letters Patent No. 75,294, dated March 10, 1868.

IMPROVED APPARATUS FOR EXTRACTING PRECIOUS METALS.

The Schedule referred to in these Letters Patent and making part of the same.

TO ALL WHOM IT MAY CONCERN:

Be it known that I, ADOLPH OTT, of the city, county, and State of New York, have invented certain Improvements in Apparatus for Extracting Precious Metals; and I do hereby declare that the following is a full and exact description thereof, reference being had to the accompanying drawings.

The nature of this invention consists in an improved apparatus, hereafter described, so constructed and combined that the desulphurizing process of the ore, tailings, or residuum from other treatments is effected in a more perfect manner than in any apparatus hitherto built for that purpose, and that the impurities or refuse of the ore are made available as reducing-agents by the construction of suitable condensers and absorbers made for that purpose.

My drawing represents a sectional elevation of my improved apparatus for extracting precious metals.

The apparatus is composed of the desulphurizing-furnace A, and of three circular ovens, C, D, and E, and of a condensing-chamber F, with appendages, as follows: G is a fireplace, having air-tight doors above and below its fire-bars, and a pipe, H, arranged to regulate the supply of air under the said fire-bars for the purpose hereafter explained. In the centre of the furnace A is placed the vertical shaft I, resting on the rest J, and having suitable gearings, K, to communicate to it at pleasure a rotary motion. L L' L'' are arms, fastened to the shaft I, and having suitable wings, scrapers, or rakers fastened thereon to agitate the mineral resting on the hearths of the ovens C, D, and E, and by their peculiar conformation to cause said mineral to travel from the centre to the circumference, and from the circumference to the centre, as hereafter described. M is the funnel-shaped pipe or flue, through which the mineral is introduced. N is the flue or passage through which the roasted mineral is discharged into the cooling-chamber O. P, P', P'', P''', P'''' and S are the flues, through which the flame, smoke, and gases find their way from the furnace G to the stack Q. R is a condensing-chamber, having a door, R', closed when the apparatus is in operation, and open to remove the products of condensation in the chamber R. T is a trough, with a perforated bottom in the manner of a shower-bath. U is a flue, circulating around the ovens in the body of the brick-work, and having a number of small holes, V V V V V, which establish a communication between the said flue U and the ovens C and D. X is the pipe coming from the blast-apparatus, fan, or blower, arranged so as to supply either cold or hot air, and having the pipe Y, through which steam may be introduced and mixed with the air to be delivered in the flue U. Z is a trough or cistern for holding the liquid running down from the stack Q and flue S.

The apparatus B is composed of the following parts: a is the apparatus for producing chlorine gas or other gases. b b are two or more tanks, closed at the top by tight trap-doors, C C, with slide-doors e e at the bottom, so that they can with facility be filled and emptied. f f is the framework, upon which the tanks b b, &c., are mounted, and g is a movable chute, which can be placed alternately under any of the tanks b b, &c. h is a centrifugal strainer, mounted on a vertical shaft, k, resting on the bearing-l, and put in motion from the pulley j, or any other suitable gearing. l is the casing of the centrifugal strainer, with its drain-pipe m, leading into the tank z. p p are pipes, leading from the apparatus a into the tanks b b, and having suitable valves, n n n, &c., to allow of the gas or gases being introduced at pleasure from the top or from the bottom in the tanks b b. r is a steam-pipe, for introducing steam at will into the tanks b b, &c.

Operation.

The desulphurizing-process is carried on in the furnace A, as follows: The pulverized ore, tailings, or residuum from other treatments, mixed or unmixed with suitable chemicals, are introduced into the oven E through the funnel M, which is kept constantly full, so as to prevent the escape of gases through it. A fire is kindled in the fireplace G, and when the ovens have attained the proper degree of heat the process begins. The shaft I is set in motion, which causes the scrapers L L' L'' to revolve. The ore in the ovens is gradually spread upon the floor, first in the oven E, from centre to circumference, until it drops by the flue P''' into the oven D, where, the hearth being depressed near the centre, the ore is brought from the circumference to the centre, dropping gradually upon the helix S to the centre of the oven C, where the scraper L', by its peculiar shape

and motion, not only spreads the ore over the hearth, but causes it to fall through the flue N into the chamber O. During the time that this mechanical movement of the ore is going on, the heat of the furnace G, in circulating through the ovens C, D, and E, accomplishes the chemical action and change required, assisted by a mixture of heated air and steam, introduced in the ovens C and D immediately over the ore, through the holes V V V V, and by other gases or vapors, and the product of the combustion of the fuel in the furnace G, managed with a proper introduction of air into the ash-pit by the pipe H.

In the process of desulphurizing or roasting the volatile metals, zinc, antimony, arsenic, sulphur, &c., will be collected in the cooling-chambers R and F, and the gases or vapors soluble in water or alkaline lye, will be absorbed in the flue S by the shower of water or lye falling from the trough T. The desulphurized ore is now introduced into the tanks b b, &c., where it is treated with gases or vapors in presence of a certain quantity of steam, and the pasty material resulting from that treatment is dropped into the centrifugal strainer h, where it is separated into two parts, the liquid portion running through the pipe m into the reservoir z, and the dry or exhausted portion remaining in the centrifugal drainer to be shovelled out, and to make room for a new charge.

Claims.

What I claim as new in my apparatus, is—

1. The ore-roasting furnace A, composed of a series of ovens, C D E, with alternate flat and depressed hearths, in combination with the shaft I, arms L L' L'', flues P P' P'' P''' P''', flues M and N, and chambers R and F, arranged and operating as set forth.
2. In an oven for roasting ore, the flue S and tank T.
3. The combination of the flue U, holes V V V V, and ovens C D E, with the pipe x and y.
4. The apparatus B, composed of the apparatus a, tank b b, and strainer h, arranged together and operating as specified.
